UNITED STATES PATENT OFFICE

2,639,919

COIN CONTROLLED BALL TEEING MACHINE

Joe Mozel, Portland, Oreg.

Application January 24, 1949, Serial No. 72,339

3 Claims. (Cl. 273—33)

1

This invention relates to coin controls and is particularly adapted for controlling the operation of golf ball teeing machines.

The primary object of this invention is to start the operation of the automatic golf ball teeing machine by a coin actuated starting mechanism.

Another object of the invention is to provide means in this coin actuated starting mechanism for predetermining the number of balls to be teed by each coin deposited in the coin receiving box associated with the timing mechanism.

A further object of this invention is to provide a coin controlled mechanism for controlling the operation of my automatic golf ball tee as disclosed in my pending application Serial No. 750,903, now Patent Number 2,520,952.

These and other incidental objects will be apparent in the drawings, specification and claims.

Referring to the drawings:

Figure 1 is a front view of my new improved coin control for golf ball teeing machines.

Figure 2 is a front view of the control device illustrating the golf ball teeing machine in broken line position, parts of the control broken away for convenience of illustration.

Figure 3 is a sectional plan view taken on line 3—3 of Figure 2.

Figure 4 is a plan sectional view taken on line 4—4 of Figure 2.

Figure 5 is a fragmentary detail view of parts of the mechanism shown in a different position than that illustrated in Figure 2.

Figure 6 is a perspective fragmentary detail of this mechanism clarifying its construction and method of mounting.

Figure 7 is a wiring diagram including parts of the control, illustrating the method of operation.

Referring more specifically to the drawings:

My new and improved coin control consists of the control and timing mechanism unit 1 and the coin actuator 2 connected together by wiring 3, referring to Figure 1. In Figure 2 I illustrate how the control and timing unit 1 is mounted to my automatic golf ball teeing machine by the screws 4, the machine being illustrated in broken lines.

Part of my control unit consists of a cam 5 which is mounted and keyed to the shaft 6 of the golf ball teeing machine. The shaft 6 revolves one revolution each time a ball is teed, and by referring to my pending application Serial No. 750,903, now Patent Number 2,520,952, the operation of this shaft is explained in detail.

The control and timing unit 1 consists of a case 7 with a cover plate 8 removably mounted thereon. A switch 9 is contained within the case 7

2

and is adapted to open or close the electric supply circuit within the golf ball teeing machine. When this switch is opened the machine will not operate, but when this switch is closed the machine will operate until the said switch is again opened. The opening and closing of the switch 9 is controlled by the actuating bar 10 in the following manner.

The actuating bar 10 is slidably mounted within 10 the guide ways 11, consisting of angle bars, best illustrated in Figures 2, 3 and 4. A cam actuated bar 12 is pivotally mounted within the casing 7 at 13 at its one end, having its opposite end resting upon the cam 5, which as stated above is 15 fixedly secured to the shaft 6 of the golf ball teeing machine. Each time the shaft 6 is rotated one revolution in the teeing of a golf ball, it will raise the bar 12, which in turn raises the bar 14 which is pivotally mounted at 15 to the casing 7 and having a pawl 16 pivotally mounted to its opposite end at 17.

When the bar 14 is raised by the bar 12 through the action of the spring connection 18 it will raise the actuating bar 10 by the pawl 16 engaging the teeth 19 of the said actuating bar, raising the said bar a predetermined amount depending upon the position of the adjustable stop screw 20. The bar is held in this position by the locking pawl 21, which is pivotally mounted to the case 7 at 22.

Each time the shaft 6 revolves in the teeing of a golf ball the actuating bar is raised a predetermined amount until its end 23 engages the switch bar 24 of the switch 9, at which time it will 30 open the switch 9 breaking the electric current supply to the golf ball teeing machine rendering the same inoperative.

When it is desired to tee and drive golf balls from the machine a coin is dropped into the coin box actuator 2. Referring particularly to Figure 7, the coin 25 will follow the chute 26 contacting the switch bar 27 closing the switch 28, which will energize the solenoid 29 through the electric supply conductors 30 and plug-in assembly 31. The switch 28 is only momentarily closed, but when the solenoid 29 pulls the bar 32 towards the said solenoid it will pull the link 33 with the same.

The link 33 is pivotally connected to the bar 32 at 34 and has a hook 35 which engages the 50 pawl 21, pulling the said pawl with the pawl 16 into engagement with the locking latch 36. This will permit the switch actuating bar 10 to drop to the position shown in Figure 5. When this happens the cam 5 will be holding the bar 12 as indicated in Figure 2 and the end 16A of the pawl

16 in engagement with the locking latch 36 as illustrated in Figure 5.

When the golf ball, not here shown, is removed from the tee, the shaft 6 will begin to rotate in the direction of the arrow, lowering the bar 12 and allowing the end 16A of the pawl 16 to release itself from the latch 36, due to the fact that the stop pin 44 limits the travel of the pawl 36. This permits the engagement of the pawls 16 and 21 with the teeth 19 of the actuating bar. When the actuating bar 10 is allowed to lower it permits the switch bar 24 of the switch 9 to permit the said switch to close completing an electric circuit through the golf ball teeing machine, so that as the balls are driven from the tee the machine will operate, teeing another ball and will keep on teeing balls until the actuating bar 10 again reaches its uppermost position engaging the switch bar 24, stopping the machine.

Due to the fact that the solenoid 29 is only energized when a coin momentarily closes the switch 28, the spring 37 will return the bar 32 to the position shown in Figure 2, allowing the pawls 16 and 21 to reengage the teeth 19 of the actuating bar 10 so that each time the cam 5 raises the cam actuating bar 12 it will raise the bar 14, together with the pawl 16 which will raise the switch actuating bar 10 the predetermined amount while the holding pawl 21 will hold the actuating bar at this point until the same is further raised by the action of the cam 5.

An adjustable stop and indicator 38 is guided within the slot 39 of the cover plate 8. This stop or indicator has a stop bar 40 extending through the slot and in alignment with the bottom 41 of the actuating bar 10. In order to determine the number of golf balls to be teed, the stop is adjusted on the scale 42 and locked in place by the locking nut 43. This will determine the amount that the actuating bar 10 drops within its guide ways 11 and the length of time it will take to raise this bar for actuating the switch 9, breaking the electric supply circuit to the golf ball teeing machine as above mentioned and described.

Although certain specific embodiments of the invention have been shown and described, it is obvious that many modifications thereof are possible. The invention, therefore, is not to be restricted except in so far as is necessitated by the prior art and by the spirit of the appended claims.

What I claim is:

1. A golf ball teeing machine having a ball feeding mechanism, a normally closed switch controlling the operation of said ball feeding mechanism, a movably supported switch opening member movable toward and retractable from said switch, means operated by the ball feeding mechanism to intermittently move the member in a given direction toward the switch upon each feeding operation to eventually open the switch after the feeding of a predetermined number of balls, and coin controlled means for releasing the member moving means whereby said member may be retracted in the opposite direction for repeat movement.
- 15 2. A game apparatus comprising a ball feeding mechanism including a driven shaft, a normally closed switch energizing the operation of said driven shaft, a toothed member mounted for movement relative to said switch for opening said switch, a cam operated by said driven shaft, pawl means engageable with said toothed member, a cam follower connected with said pawl means and operated by said cam to actuate said pawl means to intermittently advance said toothed member toward said switch each time a ball is fed and eventually open said switch after the feeding of a predetermined number of balls, coin controlled mechanism, and means operated by said coin controlled mechanism for disengaging said pawl means from said toothed member to enable retraction of said toothed member and permit normal closing of said switch.
- 20 3. A game apparatus as defined in claim 2, wherein means is provided for adjusting the movement of said pawl means to control the stroke of each movement of said toothed member relative to said switch.
